DEVICE FOR PRODUCING INFRARED RAYS

Ernst E. W. Kassner, Montana-Vermala-P/Sierre,
Switzerland, assignor to Vibranic Ltd., Glaris,
Switzerland, a society of Switzerland

Application May 19, 1947, Serial No. 749,050
In Luxembourg November 27, 1946

6 Claims. (Cl. 315—46)

1

In order to produce infra-red rays, it has been the usual practice up to the present time to make use either of incandescent lamps or of gas discharge lamps, these sources of infra-red rays having very different efficiencies. The word "efficiency" designates the transformation ratio of the electric energy supplied by a source of current or a distribution system into radiating energy.

The chief object of my invention is to improve the efficiency of devices for producing infra-red rays and more particularly the efficiency inside one or several given frequency bands.

A preferred embodiment of my invention will be hereinafter described with reference to the accompanying drawings, given merely by way of example and in which:

Fig. 1 shows in diagrammatic section the lower portion of a lamp for producing infra-red rays made according to an embodiment of my invention.

Figs. 2 and 3 are views similar to Fig. 1 and illustrating another embodiment of my invention.

Fig. 4 is an axial sectional view of an accessory device to be used in connection with the lamp of Figs. 1 to 3.

Figs. 5 and 6 are views similar to Fig. 4 and relating to modifications.

In the embodiment shown by Figs. 1 to 3, the lamp for producing infra-red rays includes a glass bulb 1, for instance of conventional shape, and the inner face of which carries a reflecting layer 2 for directing the rays towards the upper portion of the bulb. This upper portion is preferably translucent so that the beam of rays issuing from the bulb is homogeneous. According to the nature and shape of bulb 1, this inner reflecting layer 2 may be replaced by a supplementary external reflector.

Bulb 1 includes a conventional mount 3, either of the screw-threaded or of the bayonet type, through which the lamp can be directly inserted in the electric distribution system. Mount 3 is provided in the usual way with feed contacts 4 and 5. Base 6, made of insulating material, serves for the passage of wires 4a and 5a which supply current to the electrodes supported by said base 6.

The electrode system includes, on the one hand, an incandescent electrode divided into several portions (filaments) and, on the other hand, several rod-shaped electrodes each of which is housed axially in a portion of the incandescent electrode, all these electrodes being connected together as it will be hereinafter described.

In the examples shown by the drawings, I make

2

use of two filaments 7a and 7b respectively connected with their conductor supports 4b and 5b, themselves connected with feed wires 4a and 5a.

In Figs. 1 and 2, filaments 7a and 7b are connected in series and in Fig. 3 their connection is slightly different.

Each filament 7a or 7b is wound to form a helix each spire of which may be constituted either by a single winding or by a double winding.

10 In order to support the filaments, I make use of glass cylinders 8 which carry supporting wires 9 to which the filaments are directly secured. Filaments 7a and 7b are parallel to each other and to the axis of bulb 1 and they are located close to the focus of the reflector 2. They might also be disposed along the same line if it were desired to obtain a linolite lamp.

15 Electrodes 10a and 10b are constituted by small rods and each of them is fitted axially in the corresponding filament 7a or 7b. These rods 10a and 10b are kept in position by having their free ends engaged in conductor and elastic supports 11a and 11b, for instance tight-wound helical springs provided respectively at the top and bottom of each rod.

20 In the embodiment of Fig. 1, the ends of electrode 10a are connected through its supports 11a and 11b and wires 12a and 12b to feed wire 5a. Electrode 10b is connected through its supports 11a and 11b and wires 13a and 13b to feed wire 4a. Stability of the whole of the electrodes is ensured by an insulating glass piece 14 against which bear the free ends of feed wires 4a and 5a. The lower parts of these wires are separated from each other by an insulating part 15 of the base portion 6 of the lamp.

25 In the embodiment of Fig. 2, the upper ends of electrodes 10a and 10b are connected through supports 11b and wires 16 with a point 17 of the wire that connects filaments 7a and 7b with each other, whereby electrodes 10a and 10b are fed with only one half of the network voltage. The lower ends of the electrodes are connected, through supports 11a, with a piece 18 of an insulating material, itself supported by wires 19 carried by feed wires 4a and 5a.

30 The upper portion of the system of electrodes is held by a stirrup 20 constituted by a wire carried by glass cylinders 8 and which supports an insulating piece 21 through which upper supports 11b and connection wires 16 are held in position.

35 In the embodiment of Fig. 3, filaments 7a and 7b are mounted differently. Filament 7b is connected, through its lower end, with feed wire 5b and, through its upper end, with a wire 22 lead-

ing to the lower end of filament 7a. The upper end of this filament 7a is connected with a ring 23 fitted on the right hand side insulating cylinder 8 and connected with feed wire 4a. Wire 22, which connects filaments 7a and 7b together, also feeds current to electrodes 10a and 10b through a wire 16a. Wire 22 also serves to support the upper part of the electrode system in position. The lower part of this system is held in position by insulating piece 18 carried by wire elements 19.

The infra-red ray lamp of Fig. 1 works in the following manner. Supposing, for instance, that it is fed with 120 volts alternating current, filaments 7a and 7b, which are made of suitable size, grow incandescent since they are inserted in a closed circuit. As electrodes 10a and 10b are connected with feed wires 4a and 4b through wires 12a—12b and 13a—13b, their alternating voltage is equal to that of the network and as they are each placed inside an incandescent filament 7a or 7b, they are subjected to the radiations from said filaments. Once they have reached their temperature of equilibrium, they permit in turn, in the same way as takes place for the filaments, of obtaining an infra-red radiation of the same kind. The infra-red rays that are produced therefrom come both from filaments 7a and 7b and from electrodes 10a, 10b in the form of rods. Therefore, the radiating surface is very wide.

In the case of a lamp such as shown by Fig. 2, filaments 7a and 7b are fed with current in the same manner as in the case of Fig. 1, but electrodes 10a and 10b receive only one half of the network voltage since they are connected, through a wire 16, with a point half way between said electrodes.

For the lamp of Fig. 3, electrodes 10a and 10b are fed in the same manner as in the case of Fig. 2 but, due to the particular arrangement of the feed circuit of filaments 7a and 7b, the points thereof that are opposite one another respectively are always at the same potential so that it is possible to feed the lamp with a higher alternating voltage without running any risk of a spark discharge taking place between these filaments even when they are located at a short distance from each other. Therefore, this wiring arrangement is particularly advantageous when the lamp is fed with current of a voltage of 220 volts.

Electrodes 10a and 10b are made of a metal which may be the same as that of filaments 7a and 7b or different therefrom. They may consist of either solid or hollow rods. Preferably, and according to my invention, they are made of a calcined mixture of pure metals, such as tungsten, tantalum, molybdenum, and metallic salts, such as molybdenum sulphide or magnesium, zirconium or cerium oxide. With such calcined mixtures, the proportions of pure metal and metallic salt can be so chosen as to obtain a selective displacement of the maximum of radiation toward the infra-red portion of the spectrum.

As shown by Figs. 4, 5 and 6, I may, according to another feature of my invention, surround each electrode 10a or 10b with a perforated sleeve 24 made of a material having a high melting point such as zirconium oxide, magnesia, etc., this sleeve being disposed coaxially with respect to the electrode while being insulated therefrom by supports 24a. The holes 25 provided in sleeve 24 may be either circular or of elongated shape. They may be distributed in a regular manner either over the whole length of the sleeve (Fig. 4)

or, by groups, in certain portions thereof and for instance close to the ends (Fig. 5) or in the middle, etc. The area of these holes, with respect to the total area of the sleeve, is such that a predetermined screen effect is obtained for a given potential. For instance, the size of the holes averages from 0.1 to 0.5 mm. Due to the presence of the perforated sleeve, the intensity of the electronic current is limited and spark discharges are prevented. In order to obtain a good production of infra-red rays, the internal pressure may advantageously be chosen equal to 500 mm. of mercury, the bulb being filled with a mixture of argon and nitrogen.

If, according to my invention, discharge takes place in the lamp in an atmosphere of argon and nitrogen, and in the presence of a metallic vapour, more especially caesium vapour, especially when the partial pressure of caesium ranges from 0.01 to 0.001 of mercury, I obtain, simultaneously with the above mentioned production of rays, a resonance radiation of the caesium vapour which corresponds chiefly to a spectral region of 8,500 to 9,000 Å.

The location of the discharge apertures 25 of insulated sleeves 24 may be chosen, as shown by Fig. 6, in such manner that they correspond with the potential nodes 26 of the ultra-short wavelengths to be obtained. In order to determine these points, account must be taken of the existing electrical conditions, such as the network voltage, of the gas pressure in which the discharge takes place, of the distance between the sleeve and the electrode, etc. Thus it becomes possible, by means of a single system of electrodes and in the same lamp, of simultaneously producing not only infra-red rays but also rays corresponding to ultra-short waves, which involves important advantages for many applications, more especially when it is desired to act on the mass itself of matter to be treated.

My invention therefore makes it possible to obtain, by means of a single lamp, two complementary sets of electromagnetic waves, to wit one corresponding to the infra-red band (λ ranging from 0.8 to 3 μ) but close to light rays, and the other corresponding to the band of ultra-short waves (λ ranging from 0.3 mm. to 50.0 cm. approximately) which adjoins the intra-red region, while obtaining two predetermined interrelated maximums, so as to correspond, concerning a great number of organo-chemical substances, to the most important absorption rays of these substances.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A device of the type described which comprises, in combination, a bulb filled with a gaseous atmosphere, at least two radiating discharge electrodes in said bulb, constituted by parallel metal rods, at least one filament wound about each of said rods at a distance therefrom, electrical connections for causing current from the same source both to circulate in closed circuit fashion through said filaments and to bring said discharge electrodes to a given potential, whereby

infra-red rays are simultaneously radiated from said filaments and from said electrode, said electrode being within the field of the radiations of said filament, and a sleeve of a material having a high boiling point surrounding each of said electrodes, said sleeve, electrically insulated from said electrode being provided with holes.

2. A device of the type described which comprises, in combination, a bulb filled with a gaseous atmosphere, at least two radiating discharge electrodes in said bulb, constituted by parallel metal rods, at least one filament wound about each of said rods at a distance therefrom, electrical connections for causing current from the same source both to circulate in closed circuit fashion through said filaments and to bring said discharge electrodes to a given potential, whereby infra-red rays are simultaneously radiated from said filaments and from said electrode, said electrode being within the field of the radiations of said filament, and a sleeve of a material having a high boiling point surrounding each of said electrodes, said sleeve, electrically insulated from said electrode being provided with holes regularly distributed over the whole surface thereof.

3. A device of the type described which comprises, in combination, a bulb filled with a gaseous atmosphere, at least two radiating discharge electrodes in said bulb, constituted by parallel metal rods, at least one filament wound about each of said rods at a distance therefrom, electrical connections for causing current from the same source both to circulate in closed circuit fashion through said filaments and to bring said discharge electrodes to a given potential, whereby infra-red rays are simultaneously radiated from said filaments and from said electrode, said electrode being within the field of the radiations of said filament, and a sleeve of a material having a high boiling point surrounding each of said electrodes, said sleeve, electrically insulated from said electrode being provided with holes grouped at certain portions of the surface thereof.

4. A device of the type described which comprises, in combination, a bulb filled with a gaseous atmosphere, at least two radiating discharge electrodes in said bulb, constituted by parallel metal rods, at least one filament wound about each of said rods at a distance therefrom, electrical connections for causing current from the same source both to circulate in closed circuit fashion through said filaments and to bring said discharge electrodes to a given potential, whereby infra-red rays are simultaneously radiated from said filaments and from said electrode, said electrode being within the field of the radiations of

said filament, and a sleeve of a material having a high boiling point surrounding each of said electrodes, said sleeve, electrically insulated from said electrode being provided with holes grouped at the ends of the surface thereof.

5. A device of the type described which comprises, in combination, a bulb filled with a gaseous atmosphere, at least two radiating discharge electrodes in said bulb constituted by parallel metal rods, at least one filament wound about each of said rods at a distance therefrom, two terminals adapted to be connected with corresponding terminals of a source of current, two wires starting from said first mentioned terminals, said filaments being connected in series with their lower ends connected with said wires respectively, and means for connecting both ends of one of said electrodes with one of said wires and both ends of the other electrode with the other wire, whereby infra-red rays are simultaneously radiated from said filaments and from said electrode, said electrode being within the field of the radiations of said filament.

6. A device of the type described which comprises, in combination, a bulb filled with a gaseous atmosphere, at least two radiating discharge electrodes in said bulb constituted by parallel metal rods, at least one filament wound about each of said rods at a distance therefrom, two terminals adapted to be connected with corresponding terminals of a source of current, two wires starting from said first mentioned terminals, said filaments being connected in series with their lower ends connected with said wires respectively, and means for connecting both ends of one of said electrodes with the wire to which is connected the lower end of the filament wound about the other electrode and means for connecting both ends of the other electrode with the other wire, whereby infra-red rays are simultaneously radiated from said filaments and from said electrode, said electrode being within the field of the radiations of said filament.

ERNST E. W. KASSNER.
